UNITED STATES PATENT OFFICE.

JAMES HENRY DURKIN AND DAVID WILKIE, OF BATTLE CREEK, MICHIGAN.

PROCESS AND APPARATUS FOR MANUFACTURING PAPER.

Application filed March 3, 1922. Serial No. 540,942.

To all whom it may concern:

Be it known that we, JAMES HENRY DURKIN, a citizen of the United States, and DAVID WILKIE, a subject of the King of England (who has declared his intention of becoming a citizen of the United States), who reside at Battle Creek, Michigan, have invented a new and useful Improvement in Processes and Apparatus for Manufacturing Paper, of which the following is a full, clear, and exact description.

Our invention relates to improvements in the process and apparatus for manufacturing paper, and it consists in the steps hereinafter set forth and in the means for carrying out the process.

In the manufacture of paper and similar products, such as box board, it is often desirable to make the paper sheet of a width which is less than the maximum width of which the paper making machine is capable. Thus, orders are often received for sheets of less width than the maximum, and it is either necessary to cut off a strip from a sheet of maximum width, or to adjust the machine for forming a sheet of the desired width which is less than the maximum. If the latter course is pursued, it is necessary to stop the machinery. A deckle is then applied to the cylinder mold. This consists of one or more strips of cotton tape which is wrapped around the cylinder mold near one end thereof. The deckle will not pick up the paper stock from the vat, and consequently the width of the sheet is narrowed by the width of the deckle.

One object of our invention is to provide a process by means of which the width of the sheet of paper may be gauged and determined in the forming thereof without the necessity of stopping the machinery.

A further object of our invention is to provide a process for regulating the width of the paper sheet without the necessity of attaching anything to the cylinder mold, such as the ordinary deckle.

A further object of our invention is to provide a novel means for carrying out the steps of the process, these means being simple in construction, and being readily applicable to paper or box board machines of existing types.

A further object of our invention is to provide a process and means whereby a material saving in paper stock, as well as in labor, is effected.

Other objects and advantages will appear in the following specification, and the novel features of the invention will be particularly pointed out in the appended claims.

Our invention is illustrated in the accompanying drawings, forming part of this application, in which—

Figure 1 is a sectional view through a pulp tank with our invention applied thereto,

Figure 2 is an enlarged section through a water pipe and the water controlling device,

Figure 3 is a section along the line 3—3 of Figure 2,

Figure 4 is a section along the line 4—4 of Figure 2, and

Figure 5 is a diagrammatic view, showing the relation of the cylinder mold to the water pipe.

In the drawings, we have illustrated only those parts of the paper making machine which are directly concerned with the invention. At 1 we have shown a tank or pulp vat containing the paper pulp mixture 2. The cylinder mold 3 is mounted for revolution in the vat, and is provided with the usual wire gauze covering 4 which takes up the pulp in the revolution of the cylinder mold preparatory to the forming of the sheet.

At 5 we have shown a portion of supporting members which are to be found on the typical machine. In these supporting members we mount pipes 6 which extend parallel with the cylinder mold and are disposed above the axis of the cylinder mold and to one side thereof, as shown in Figure 5. In the drawing, we have shown a plurality of these pipes, but it is obvious that one might be used alone without departing from the spirit of the invention. The pipe 6 passes through the support 5 and communicates at its outer end with the interior of a valve casing 7 provided with a valve 8 which controls a supply of water from any suitable source (not shown).

A T 9, which establishes communication between the end of the pipe 6 and the valve casing 7, is provided with a packing gland 10, through which a rod 11 passes. This rod 11 is provided with a scraper 12 which is arranged to engage the interior of the pipe 6. It is also provided at its end with a perforated head 12^a. A screw cap 12^b is secured to the end of the pipe. The pipe 6 is provided with a series of inclined openings

13 for the discharge of water from the pipe.

Slidably disposed on the pipe is a sleeve 14 provided with a milled portion 15. The sleeve, while slidably, nevertheless fits tight enough to cover the openings 13 when it is desired to prevent the escape of water from any of the openings.

From the foregoing description of the various parts of the device, the operation thereof may be readily understood. When it is desired to make a strip of paper the full width of the cylinder mold, the valve 8 is closed to prevent the entrance of water into the pipe 6, or the sleeve 14 may be moved manually to cover the openings 13. If, however, it is desired to make a sheet of paper of less than the maximum width, then the sleeve 14 is moved to uncover a series of openings 13 of the pipe so as to permit the projection of streams of water through the openings when the valve 8 is opened to permit the entrance of water, and thus to wash off from the cylinder mold a strip of paper pulp or stock which has been taken up by the cylinder mold, thus returning the stock to the vat and limiting the width of the sheet accordingly. In Figure 1, we have shown two pipes 6, each sending streams of water 16 outwardly so as to wash off the portion of the stock taken up by the cylinder mold.

Obviously, if the valve 8 is shut so as to prevent the admission of water, the edges of the sheet will not be washed off and hence the sheet would be of the maximum width. The sleeve 14 is easily shifted during the running of the machine and can be set at any predetermined position or adjusted position to regulate the width of the sheet.

By manipulating the rod 11 through the medium of the handle 17, the interior of the pipe 6 may be cleaned of any obstruction that might tend to clog up the openings 13. Thus the scraper 12 may be passed over that portion of the pipe bearing the openings 13, or the rod may be moved longitudinally to cause the perforated plate to act as a scraper, thus dislodging any matter which may have collected on the interior of the pipe, and permitting it to pass out with the stream of water. In order to permit the plate 12^a to move freely in the pipe 6 when it is filled with water, it is perforated, as shown.

It may be sometimes necessary to adjust the angle of the discharge of the stream of water with respect to a tangent to the cylinder mold at the point of contact of the stream with the cylinder mold. Thus in Figure 5, we have shown the stream 16 as striking the cylinder mold at a point X. It may be desirable to have the stream strike the mold at a point lower down or higher up than that shown. The best position is that position in which the pulp is washed away

from the main body portion of the sheet, and in which there is no splashing on the portion left which might tend to injure or to wash out parts of the main body portion. In other words, there is an angle at which the stream may be directed which will cause the effective washing off of the pulp so as to leave a substantially clean-cut edge for the sheet. In order to vary the angle at which the stream 16 is projected, we provide means, such as the milled hand grip 18 on the pipe, for turning the latter to the proper position. It will be noted that the pipe is held in the support 5 and that the T is screwed up against this support. It will be understood, however, that this angular adjustment is a very slight one and that by grasping the pipe and turning it, the angular inclination of the stream may be changed as desired.

This process obviates the necessity of running the stock again through the mill, as must be done where a strip is cut off from the full width of the sheet. It also obviates the necessity of stopping the paper making machine, as for instance, when the ordinary tape deckle is used. This stopping of the machine results in a loss of time and labor.

The device is very readily installed on machines of existing types and is comparatively simple in operation, and hence does not get out of order.

We claim:

1. A device of the type described comprising a pipe having a plurality of openings therein, a rod rotatably disposed in said pipe and having a lateral projection adapted to engage with the inner surface of said pipe, and a perforated disc carried by the inner end of said rod, the periphery of said disc snugly engaging the inner wall of said pipe.

2. In a process of paper manufacture, the step of determining the width of the paper sheet which consists in directing a stream of water upon a cylinder mold for washing from the cylinder mold a portion of the paper pulp taken up by the cylinder mold, the stream of water being projected outwardly at an angle to the main body of the sheet carried by the cylinder.

3. The combination with a pulp retaining tank and a cylinder mold carried by said tank, of means for directing a stream of water upon said cylinder, said means directing the water outwardly at an angle to the main sheet of paper formed upon the cylinder.

4. The combination with a cylinder, of a water pipe disposed parallel with respect to the cylinder, said pipe having outlet openings extending at an angle, said openings being adapted to direct the water upon said cylinder outwardly at an angle to the main body of the cylinder.

5. The combination with a cylinder, of a water pipe disposed parallel with respect to

the cylinder, said pipe having outlet openings extending at an angle, said openings being adapted to direct the water upon said cylinder outwardly at an angle to the main body of the cylinder, and sleeves carried by said pipe and being adapted to close part or all of the water outlet openings in said pipe.

6. The combination with a cylinder, of a water pipe disposed parallel with respect to the cylinder, said pipe having outlet open-

ings extending at an angle, said openings being adapted to direct the water upon said cylinder outwardly at an angle to the main body of the cylinder, and sleeves carried by said pipe and being adapted to close part or all of the water outlet openings in said pipe, said pipe being adapted to turn on its longitudinal axis.

JAMES HENRY DURKIN.
